(57) **CLAIM**

The ornamental design for a urinary catheter assembly, as shown and described.

DESCRIPTION

FIG. 1 is an isometric view of a design for a urinary catheter assembly;

FIG. 2 a top side view thereof;

FIG. 3 a bottom side view thereof;

FIG. 4 is a back side view thereof, where a front side view is not illustrated as it is a mirror image of the back side view;

FIG. 5 is a right side view thereof;

FIG. 6 is a left side view thereof; and,

FIG. 7 is a view of an enlarged portion of a handle of the urinary catheter assembly from FIG. 1.

In FIG. 1 and FIGS. 5-6 the broken lines form no part of the claimed design.

The dot-dash broken lines represent boundaries of the enlarged portion and form no part of the claimed design.
